UNITED STATES PATENT OFFICE.

JOSEPH ENIS, OF JERSEY CITY, NEW JERSEY, ASSIGNOR TO BIGELOW HARTFORD
CARPET COMPANY, A CORPORATION OF MASSACHUSETTS.

DESIGN FOR A RUG.

51,779.

Specification for Design.

Patented Feb. 19, 1918.

Application filed December 20, 1917. Serial No. 208,180. Term of patent 7 years.

To all whom it may concern:

Be it known that I, JOSEPH ENIS, a citizen of the United States, residing at Jersey City, in the county of Hudson and State of New Jersey, have invented a new, original, and ornamental Design for a Rug of Carpet Size, of which the following is a specification, reference being had to the accompanying drawing, forming part thereof.

The drawing illustrates a portion of a rug, showing my new design.

I claim:

The ornamental design for a rug substantially as shown.

JOSEPH ENIS.
